UNITED STATES PATENT OFFICE.

JAMES E. POTTER, OF PROVIDENCE, RHODE ISLAND.

LOCKET.

SPECIFICATION forming part of Letters Patent No. 727,555, dated May 5, 1903.

Application filed November 20, 1902. Serial No. 132,052. (No model.)

To all whom it may concern:

Be it known that I, JAMES E. POTTER, a citizen of the United States, residing at Providence, in the county of Providence and State 5 of Rhode Island, have invented certain new and useful Improvements in Lockets, of which the following is a specification.

My invention relates to lockets and similar articles, and has for its purpose a concealment of the joint, which shall possess the advantages of a swinging and pivoted joint and hinge combined, so that the locket-cover shall not only be limited in its outward movement, but shall at all times be in intimate contact 15 with the body portion, thus escaping the disjointed effect presented by the structures heretofore devised.

To these ends my invention consists in the construction and combination of parts hereinafter described, and illustrated in the accompanying drawings, wherein—

Figure 1 is a face view of my complete locket; Fig. 2, an edge view; Fig. 3, a transverse section of the locket on line 3 3 of Fig. 25 1; Fig. 4, a plan view of an inner portion of the locket-body; Fig. 5, a section of the latter on line 5 5 of Fig. 4; Fig. 6, a plan view of an inner portion of the locket-cover; Fig. 7, a section of the latter on line 7 7 of Fig. 6; Fig. 8, a front view of the joint upon open 30 cover; Fig. 9, a vertical section of the same on line 9 9 of Fig. 8, and Figs. 10 and 11 detail views of the joint.

Like letters of reference indicate like parts 35 throughout the views.

The structure of my locket is as follows: The curved body portion A of my locket has an internal flange a, with a depressed portion a' adjacent a marginal slot or opening a² 40 therein. The locket-cover B is similar in outline to the body portion and has a like inner flange b. The latter has a reduced depressed portion b', which forms a rectangular opening c in the flange upon one side of the reduced portion and a segmental recess b² on the other side. The usual suspension-ring d is fixed to the margin of the body, and a catch e projects from the flange a at a point diametrically opposite the joint parts now to be described. A hinge-plate m is soldered into the flange depression a'. The plate is thus flush with the surface a. The margin of the plate is

provided with two slots and rolled to embrace a pintle n, which also traverses two bars o, seated in the slots, and whose opposite ends 55 are also transversely pierced to receive a second pintle p, which similarly pivots the bars to the rolled slotted margin q of the hinge-plate r. The extremity of the bars o adjacent the plate r project somewhat beyond the pintle 60 p and are downwardly beveled, Fig. 11. The plate r is soldered to the inner face of the cover B, allowing the joint parts to operate in the opening c of the flange b. The opening a² in the body-flange affords a clearance-space for 65 the bearings of pintle n. It will be observed that in closed position, Fig. 3, the joint is folded inwardly, requiring a minimum of thickness in the completed locket, which is a desideratum in this class of jewelry, and the 70 surfaces of the locket body and cover are flush with each other, entirely concealing the hinge. In open position, Fig. 9, the pivotal bars o swing outwardly sufficiently to throw the edge of the cover B outside the edge of the 75 body A, and the latter rests in the segmental recess b² of the cover. The bars o are of sufficiently-restricted length to check any excessive disclosure of the locket parts and hold the latter in close contact with each other in 80 all positions.

While I consider two pivoted bars o preferable, it is obvious that my device would be operative if one bar be eliminated.

Having thus described my invention, I 85 claim—

1. In a locket, the combination with the body of an internal marginal flange, a hinge-plate fixed to said flange, a cover, an internal marginal flange upon the cover, a hinge-plate 90 fixed to the cover, and bars intermediate the hinge-plates and pivoted thereto.

2. In a locket, the combination with the body of an internal marginal flange, a hinge-plate fixed to said flange, a cover, an internal 95 marginal flange upon the cover, parallel bars hinged to the hinge-plates and provided upon the extremities adjacent the cover with beveled extensions.

3. In a locket, the combination with the 100 body of an internal marginal flange provided with a depression a hinged plate seated in the depression, a cover, an internal marginal flange upon the cover provided with a de-

pressed and reduced portion, a rectangular marginal recess upon one side of the reduced portion, a segmental depression upon the other side of said portion, a hinge-plate fixed to the cover beneath the flange thereof, means intermediate the hinge-plates and pivoted thereto for regulating the travel of the cover, and a slot near the margin of the body to receive the pivoted means when the latter are in folded position.

4. In a locket, the combination with the body of an internal marginal flange, a hinge-

plate fixed to said flange, a cover, an internal marginal flange upon the cover, a hinge-plate fixed to the cover, and a bar within the locket 15 intermediate the hinge-plates and pivoted thereto.

In testimony whereof I have affixed my signature in presence of two witnesses.

JAMES E. POTTER.
